UNITED STATES PATENT OFFICE.

ROBERT MEGOW, OF MINNEAPOLIS, MINNESOTA.

HEEL AND SHANK SUPPORT.

1,273,080.

Specification of Letters Patent. Patented July 16, 1918.

Application filed April 8, 1918. Serial No. 227,174.

To all whom it may concern:

Be it known that I, ROBERT MEGOW, a citizen of the United States, residing at Minneapolis, in the county of Hennepin and 5 State of Minnesota, have invented certain new and useful Improvements in Heel and Shank Supports; and I do hereby declare the following to be a full, clear, and exact description of the invention, such as will enable others skilled in the art to which it 10 pertains to make and use the same.

My present invention has for its object to provide an extremely simple and highly efficient heel and shank support or reinforcement especially adapted for use to reinforce 15 and support the high heels of ladies' shoes.

These high heels which vary in type from what is known as the Cuban, military, or French heels, are almost certain sooner or 20 later to lose position in respect to the shoe, because there is an inherent weakness at the point where the shank passes under the heel and because these high heels produce great strain at such points.

Various devices have been devised for reinforcing these heels and holding the same in position, but all thereof known to me have been subject to one or more serious defects. It is the common practice in heels of the 25 above character to drive a long nail through the heel midway between the sides and quite close to the front of the heel. A single pointed reinforcement when centrally located will almost invariably strike this nail 30 and be deflected out of its proper central position.

The improved device which is the subject of this application, is stamped or pressed from a single piece of sheet steel and is 40 formed at its chisel or wedge end with a pair of laterally spaced flat chisel-like pointed prongs with a V-shaped centering notch between them. The so-called heel support is best when made of thin sheet steel and when 45 made of such material requires a stiffening corrugation to give the desired strength to support the heel. This corrugation is pressed from the under side of the reinforcing plate, is extended less than from end to end 50 of the plate, and one of its corrugations runs out or disappears at the apex of the centering notch.

In the accompanying drawings which illustrate the invention, like characters in-

dicate like parts throughout the several 55 views.

Referring to the drawings:

Figure 1 is a perspective view showing an inverted shoe with the heel and shank support applied to the shoe;

Fig. 2 is a fragmentary view in perspective, showing the support, a portion of the shoe being indicated by dotted lines;

Fig. 3 is a longitudinal section on the line 3—3 of Fig. 2;

Fig. 4 is a transverse section on the line 4—4 of Fig. 2;

Fig. 5 is a side elevation with some parts broken away and some parts sectioned, showing a shoe with the support applied; and

Fig. 6 is a side elevation showing a breakdown heel before the shank is applied.

The shoe is indicated as an entirety by the numeral 7. The heel and shank reinforcement is, as stated, stamped or pressed from a single piece of thin sheet steel 8 which preferably has a spring temper or, at any rate, is very stiff and, at the same time, not brittle. At its driving end it has the laterally spaced, chisel edged pointed prongs 9 and between them the V-shaped centering notch 10. Its reinforcing corrugation 11 has maximum depth at its central portion and diminishes to zero at its ends. At its front end this reinforcing corrugation 11 extends to the apex of the centering notch 10 so that it has its maximum reinforcing action, that is reinforces the plate up to the very apex of the notch. At its outer end the plate is provided with holes through which small screws or nails, such as the "Baker Holdfast" are passed and screwed or driven into the shank of the shoe.

In applying this support, it is first advisable to insert a screw driver, for instance, at the breast of the heel, far enough to allow the plate to be slightly inserted. Then drive the plate or support between the shank and heel until the apex or centering notch strikes against the nail 7^a of the heel. This in a new shoe will reinforce the heel so that it will always maintain its proper position, and when thus applied in a dilapidated heel will force the same back to its proper position and thereafter support the same in the proper or original position.

The nail of the heel instead of being an obstruction is thus utilized to properly cen-

ter the reinforcing plate or so-called shank and heel support and the corrugation of the plate will extend its reinforcement from the nail forward to a point considerably in front of the heel. The strongest part of the reinforcing corrugation 11 will then be at approximately a point of junction between the shank and the heel of the shoe, and there will be no danger of breaking or bending 10 of the shoe at that point.

Obviously, the so-called shank and heel support construction, such as described, may be made in quantities at very small cost and, moreover, may be easily applied either to 15 old or new shoes with the desired results stated.

What I claim is:

1. A heel and shank supporting plate for shoes stamped from a single piece of sheet metal, and formed at its driving end with laterally spaced flat prongs with a V-shaped centering notch between them, the said plate having a displaced centrally located longitudinal corrugation diminishing and terminating at the apex of said centering notch. 20
2. The combination with a shoe having a centrally located nail in the heel thereof, of a heel and shank supporting plate having at its driving end laterally spaced flat prongs 30 with a V-shaped centering notch between them, the said plate being driven into the heel adjacent to the shank with the prongs

straddling the said nail and centered thereby, the outer end of said plate being secured to the shank of the shoe. 35

3. The combination with a shoe having a centrally located nail in the heel thereof, of a heel and shank supporting plate having at its driving end laterally spaced flat prongs 40 with a V-shaped centering notch between them, the said plate being driven into the heel adjacent to the shank with the prongs straddling the said nail and centered thereby, the outer end of said plate being secured to the shank of the shoe, and the said plate 45 having a displaced reinforcing corrugation diminishing and terminating at the apex of said centering notch.

4. A heel and shank support plate for 50 shoes stamped from a single piece of sheet metal, the completed plate having substantially the same thickness throughout, and provided with a laterally displaced corrugation tapering toward its driving end and disappearing short of its driven end and 55 adapted to follow the driving end into the heel of the shoe under the driving action.

In testimony whereof, I affix my signature in presence of two witnesses.

ROBERT MEGOW.
